JACK COLUMN CONSTRUCTION

George H. Dean, Norwood, R. I.

Application June 16, 1949, Serial No. 99,477

6 Claims. (Cl. 254—98)

1

The present invention relates to support columns, and has particular reference to a novel construction for a jack column.

The principal object of the invention is to provide a jack column which has interlocking parts, whereby the column cannot collapse upon failure of the jack screw or upon disengagement of the jack screw at maximum lift.

Another object of the invention is to provide a jack column with a screw shield, for preventing damage to the screw threads.

A further object is to provide a jack column with a support top which relieves the screw against excessive pressures resulting from unavoidable tilting of the upper contact plate.

An additional object of the invention is to improve the screw housing and its permanent mounting in the support column.

With the above and other objects and advantageous features in view, the invention includes a novel arrangement of parts more fully disclosed in the detailed description following, in conjunction with the accompanying drawings, and more specifically defined in the claims appended thereto.

In the drawings,

Fig. 1 is a front elevation of a column jack embodying the invention, parts being broken away;

Fig. 2 is a vertical section on the line 2—2 of Fig. 1, jack being in low position;

Fig. 3 is a sectional detail showing the upper jack parts when in extreme raised position;

Fig. 4 is a plan view of the upper contact plate;

Fig. 5 is an enlarged sectional detail of the upper part of the jack column;

Fig. 6 is a section showing the jack screw housing and the upper cylinder parts;

Fig. 7 is a bottom plan view of the housing;

Fig. 8 is a top plan view of the jack screw and its shield; and

Fig. 9 is a sectional detail of a modified mounting arrangement for the jack screw and its shield.

It has been found desirable to provide an improved jack column which is safe, which cannot collapse, and which remains permanently rigid under compression stresses even when the pressure conditions are slightly off-vertical. To this end, I have rigidly locked a jack screw housing into a support column, preferably with solidified concrete, and I have equipped the jack screw with a lower extension and with a shield which telescopes with respect to the jack screw housing and the upper end of the support column so that failure of the jack screw or separation threading of the jack screw out of the housing

2

cannot release the jack screw from the column. I have further provided the jack screw with an auxiliary top which engages the upper contact plate whenever it is subject to unavoidable tilting, the parts being so arranged that excessive bending stress on the jack screw is distributed and relieved.

Referring to the drawings, the novel jack column 10 includes the usual base plate 11, support column 12, and upper contact plate 13, which is adapted to be raised by means of a jack screw 14, as hereinafter described.

The base plate 11 is preferably circular, and has an annular upwardly extending flange or rim 15 in which the lower end 16 of the column 12 seats. The column 12 is tubular, of preferably cylindrical form, and has a jack screw housing 17 mounted in its upper end, the housing 17 being hollow, with an annular flange 18 which has a plurality of spaced depending bosses 19, see Figs. 6 and 7, preferably four in number. Each boss 19 has a peripheral recess 20, and suitable corresponding openings 21 are provided in the column wall, whereby welding material 22 may be applied to permanently lock the housing to the column.

As clearly shown in Fig. 2, the housing 17 has a lower extension 23, which may have an opening 24 closed by a threaded closure plug 25, whereby the column 12 may be filled with concrete 26 without entry or seepage of concrete into the housing. The spaced bosses lock to the concrete and provide a firm grip between the housing and the concrete. The upper end 27 of the housing preferably slightly tapers and has a thickened top 28 which is bored and threaded as indicated at 29 to provide a rigid support for the threads of the jack screw 14.

The jack screw has a depending reduced extension 30 at its lower end, and a reduced upper portion 31 which is stepped down to provide a bearing shoulder 32 and a centering plug 33 adapted to seat in the central opening 34 of the upper contact plate 13. The upper plate 13, see Figs. 4 and 5, is generally square, with bolt or screw holes 35 for attachment to the under surface of a floor beam or the like, and has an annular bearing collar 36 for engaging the jack screw shoulder 32, a secondary bearing shoulder 37 spaced from the shoulder 32 and connected thereto by radial ribs 38, and an annular depending ridge 39.

The jack screw is provided with a shield 40, see Figs. 2 and 3, in the form of a cup with a wall 41 of tapered section depending from a support

3

plate 42, which is welded to the upper portion 31 of the jack screw, as by applying welding metal into recesses 43 in the plate 42 adjacent the upper jack screw portion 31. The depending wall 41 is positioned intermediate the outer wall of the housing 27 and the upper end 44 of the column 12, and the support plate 42 has spaced annular ridges 45 which rest within the contact plate ridge 39 and are adapted to engage the secondary bearing shoulder 37 if the upper contact plate 13 is tilted, to thus distribute and relieve the compression strain on the jack screw shoulder 32. The support plate 42 has a transverse bore 45 to receive the end of a turning pipe or rod, for turning the jack screw, and has a preferably hexagonal periphery to permit turning by means of a wrench if desired.

Should the jack screw break for any reason, the telescoping relation of the upper column end 44, the shield 40 and the housing 27 prevent collapse of the jack column. Also, if the jack screw is turned to screw out of the housing, see Fig. 3, it cannot leave the housing, as the lower end 30 merely rotates, whereby collapse is prevented. The shield 40 effectively prevents access to the jack screw and damage to the threads.

If desired, the locking between the shield support plate 42 and the upper jack screw portion 31 may be increased by recessing the portion 31 as indicated at 46 as well as the plate 42 to receive welding metal, as illustrated in Fig. 9, the number of recesses being also increased.

Although I have described a specific constructional embodiment of the invention, it is obvious that changes in the size, shape and arrangement of the parts may be made to suit different requirements for column jacks, without departing from the spirit and the scope of the invention as defined in the appended claims.

I claim:

1. In a jack column, a support column, a jack screw housing secured within the upper end thereof, a jack screw threaded in said housing, a contact plate mounted on the upper end of the jack screw, and a shield element secured to the upper end of the jack screw and having a depending wall positioned in intermediate telescoping relation to the column upper end and the jack screw housing.

2. In a jack column, a support column, a jack screw housing secured within the upper end thereof, a jack screw threaded in said housing,

4 a contact plate mounted on the upper end of the jack screw, and a shield element secured to the upper end of the jack screw and having a depending wall positioned in intermediate telescoping relation to the column upper end and the jack screw housing, said jack screw having a reduced extension at the lower end thereof.

3. In a jack column, a support column, a jack screw housing secured within the upper end thereof, a jack screw threaded in said housing, a contact plate mounted on the upper end of the jack screw, and a shield element secured to the upper end of the jack screw and having a depending wall positioned in intermediate telescoping relation to the column upper end and the jack screw housing, said contact plate having an annular depending ridge.

4. In a jack column, a support column, a jack screw housing secured within the upper end thereof, a jack screw threaded in said housing, a contact plate mounted on the upper end of the jack screw, and a shield element secured to the upper end of the jack screw and having a depending wall positioned in intermediate telescoping relation to the column upper end and the jack screw housing, said contact plate having an annular depending ridge, and a supplemental annular bearing shoulder, and said shield element having an upper plate adapted to seat within the contact plate ridge.

5. A jack screw housing for a jack column, having an elongated hollow body, an annular flange adjacent the lower end thereof, and spaced bosses depending from said flange, the upper end of the housing being threaded to receive a jack screw.

6. A jack screw housing for a jack column, having an elongated hollow body, an annular flange adjacent the lower end thereof, and spaced bosses depending from said flange, the upper end of the housing being threaded to receive a jack screw, the bosses having recesses adapted to receive welding metal.

GEORGE H. DEAN.
